United States Patent Office.

CHARLES PARKER, OF MERIDEN, CONNECTICUT.

Letters Patent No. 95,258, dated September 28, 1869.

IMPROVED VISE.

The Schedule referred to in these Letters Patent and making part of the same.

To all whom it may concern:

Be it known that I, CHARLES PARKER, of Meriden, in the county of New Haven, and State of Connecticut, have invented a new Improvement in Auxiliary Jaws for Vises; and I do hereby declare the following, when taken in connection with the accompanying drawings, and the letters of reference marked thereon, to be a full, clear, and description of the same, and which said drawings constitute part of this specification, and represent, in—

Figures 1 and 2, end views of the two jaws;

Figures 3 and 4, top views of the same;

Figures 5 and 6, front and rear views, respectively; and in

Figures 7 and 8, central sections.

This invention relates to an improvement for attachment to the jaws of vises, in order that the same jaws may serve for gripping cylindrical articles, as pipe, &c., and consists in the construction of an auxiliary jaw, to set on over each of the principal jaws of a vise, and the two auxiliary jaws formed so that the central part of one will project and enter into a corresponding central recess on the other auxiliary jaw, and the two jaws cut out on their meeting-surfaces at nearly an angle of forty-five degrees, both upon the upper and lower edge toward the centre.

To enable others skilled in the art to make and use my invention, I will proceed to describe the same as illustrated in the accompanying drawings.

A represents one auxiliary jaw, B, the other, formed as seen in the several figures; so that each of the auxiliary jaws will set respectively over the jaws of a vise, as seen in figs. 7 and 8, the jaws of the vise being denoted in broken lines.

Upon the inside of one of the auxiliary jaws A, I form or attach two cheeks, C, projecting from the auxiliary jaw inward, the inner edge of the said cheek formed as seen in figs. 1 and 7, that is, cut back from the upper and lower edge at an angle of about forty-five degrees.

Upon the other auxiliary jaw B, I form or attach a single cheek, D, in such relative position to the two cheeks C, upon the other auxiliary jaw, that the cheek D will pass between the two cheeks C C, as seen in figs. 2 and 4.

The edge of the cheek D is cut back in like manner as the cheek C, as seen in figs. 2 and 8, so that as the two auxiliary jaws upon their respective principal jaws are forced together, as seen in figs. 7 and 8, they will grasp whatever is placed between them, and especially adapted for grasping pipe and like cylindrical articles.

I do not wish to be understood to claim, as my invention, the arrangement of the jaws so that one will pass between the two opposite jaws, as such, I am aware, is very old; but

What I do claim, and desire to secure by Letters Patent, is—

The auxiliary jaws A and B provided respectively with the cheeks C and D, all constructed and applied to the jaws of a vise, substantially as described and in the manner set forth.

CHAS. PARKER.
